UNITED STATES PATENT OFFICE

2,549,329

BARRELMAKER FOR TOY BARRELS

Clayton James Niebuhr, Dearborn, Mich.

Application January 7, 1946, Serial No. 639,594

1 Claim. (Cl. 147—3)

1

The invention relates to a constructive toy, and more especially to a toy barrel making device.

The primary object of the invention is the provision of a device of this character wherein a youngster can operate it for the formation of miniature barrel bodies, including the setting of the staves, heads and hoops under the assembly thereof, the device being of novel construction and is unique in the arrangement of its cooperating parts.

Another object of the invention is the provision of a device of this character wherein as a unit it is a toy, and in the operation thereof is educational, retaining the interest of a youngster and affording instructions in barrel making.

A further object of the invention is the provision of a device of this character, which is simple in construction, readily and easily operated, strong, durable, possessed of few parts, thus devoid of complicated mechanical set-up, readily portable, fascinating to handle or operate, creative in the working and inexpensive to manufacture.

With these and other objects in view the invention consists in the features of construction, combination and arrangement of parts as will be hereinafter more fully described and my invention is illustrated in the accompanying drawing, which discloses the preferred embodiment of the invention, and pointed out in the claim hereunto appended.

In the accompanying drawing:

Figure 1 is a perspective view of the device, showing initially the setting of staves for a miniature barrel.

Figure 2 is a perspective view showing the barrel completed through the use of the device in the making thereof.

Similar reference characters indicate corresponding parts throughout the several views in the drawing.

Referring to the drawing in detail, the device constituting the present invention, which in its nature is a toy, comprises a stand denoted generally at A, and involves a base or bed 10 from which rise opposed vertical end pieces 11, which are of uniform height to each other.

The end pieces 11 support a top slab or panel 12, which at a central area thereof is provided with a half-circular recess 13, while superimposed on the base or bed 10 is a platform 14 having underslung sills 15 which raises the platform a slight distance elevated to the upper face of the base or bed, while provided in the said platform is a round opening 16 adapted to have one-half thereof register with the recess 13 in super position thereto.

Mounted for vertical swinging movements by hinges 17 is a tilted substantially U-shaped treadle 18, its side bars or branches 19 having the hinges 17 connected thereto, which hinges being further connected to the base or bed 10, with the treadle 18 straddling the platform 14 as best seen in Figure 1 of the drawing.

2

The treadle 18 at the side branches 19 thereof has anchored thereto the ends of a looping strand or cable 20, which has the ends joined to the branches loosely threaded through holes 21 formed in the top slab or section 12 spaced from and opposite sides of the recess 13 therein, so that a loop formation 22 in such strand or cable 20 can be tightened or slackened in coinciding relation to such recess.

10 In the making of miniature barrels, a complete one being denoted at B, in Figure 2 of the drawing, initially loose staves, each indicated at 23 is set in position, after the placement of the lowermost hoops 24 have been placed on for encircling the lower portion of the required number of staves for the assembly of the barrel body A above the platform, to have the loop formation 22 embrace this assembly, then by tightening the formation 22 about such assembly, the upper loops 24 are fitted about the upper portion of the assembly, when the barrel body A has been completed, and thereafter the end heads, one being indicated at 25, can be fitted to this body, with a resultant barrel being completed.

15 25 The formation 22 is controlled by operating the treadle 18, by the foot of a person using the device.

20 The stand may also be used for taking a barrel apart by placing the barrel in the stand, applying the coil in the rope around the upper end of the barrel and tightening the rope by the foot treadle. With the staves drawn together by the rope the hooks may readily be removed wherein the staves are released.

25 35 What is claimed is:

30 In a toy barrel making device, a stand, a base for said stand, a top slab above said base, said top slab having a half circular recess, a platform separate from said base and removable therefrom, but positioned thereon, said platform having a circular opening for vertical alignment with said recess in said top slab, a tightening and slackening cable located above said top slab, said cable having a loop formation therein for registering with said recess in said top slab, and 40 a foot treadle having side bars hinged to said stand at a point below the top slab thereof for controlling the tightening and slackening operation of said cable, opposite ends of said cable passing through apertures in said top slab, and being secured to the said side bars of said treadle, thus providing an operative connection between said cable and said treadle.

CLAYTON JAMES NIEBUHR.
